(57) **CLAIM**

The ornamental design for a dispenser for cosmetics as shown and described.

DESCRIPTION

FIG. 1 is a perspective view of a first embodiment of a dispenser for cosmetics, embodying our new design;

FIG. 2 is a front view thereof;

FIG. 3 is a back view thereof;

FIG. 4 is a left view thereof;

FIG. 5 is a right view thereof;

FIG. 6 is a top view thereof; and

FIG. 7 is a bottom view thereof.

FIG. 8 is a perspective view of a second embodiment of a dispenser for cosmetics, embodying our new design;

FIG. 9 is a front view thereof;

FIG. 10 is a back view thereof;

FIG. 11 is a left view thereof;

FIG. 12 is a right view thereof;

FIG. 13 is a top view thereof; and,

FIG. 14 is a bottom view thereof.

In the drawings, the broken lines show portions of a dispenser for cosmetics that form no part of the claim.
